FIG. 3.

UNITED STATES PATENT OFFICE.

HARRY G. WEBSTER, OF CHICAGO, ILLINOIS, ASSIGNOR, BY MESNE ASSIGNMENTS, TO
JAMES R. GARFIELD, TRUSTEE, OF CLEVELAND, OHIO.

TELEPHONE-EXCHANGE SYSTEM.

1,266,645.

Specification of Letters Patent. Patented May 21, 1918.

Application filed May 29, 1914. Serial No. 841,798.

To all whom it may concern:

Be it known that I, HARRY G. WEBSTER, residing at Chicago, in the county of Cook and State of Illinois, have invented a new and useful Improvement in Telephone-Exchange Systems, of which the following is a specification.

My invention relates to telephone exchange systems, and particularly to that type of systems known as call distributing systems, in which the lines of calling subscribers are automatically extended to any one of a plurality of operators' positions at which the call is answered. The desired connection is then completed by means under control of the operator who has answered the calling line. The object of my invention consists in the provision of improved means for automatically extending a calling line to an idle operator whereby greater speed and reliability of operation than has heretofore been possible is secured.

In prior call distributing systems in which calling lines are automatically extended to trunk lines terminating in plug ended cords, traveling switches have been employed interposed between the calling lines and the trunks for effecting the automatic extension of the called lines. In accordance with the present invention, I avoid the use of traveling switches operated in response to each call, and instead secure the automatic extension of the calling lines by means of correlated relay groups associated with each trunk line. A sufficient number of trunk lines are associated with each line group to care for the maximum calling traffic present at any one time in the line group, and these trunk lines terminate in plug ended cords before answering operators. The relays of each such group are selectively operated to connect a calling line with the trunk line to which the relays belong, and a relay associated with each trunk line operates at the instant of selection to temporarily disassociate from the line group that trunk line thus engaged. In addition, each line group and associated trunk group is provided with a guarding switch and controlling devices so arranged that in case of abnormal delay or defective operation at the time of selection, the switch will be op-

erated to disassociate that portion of the apparatus in defective condition.

I have illustrated a preferred embodiment of my invention in the accompanying drawings, in which Figure 1 and Fig. 2 illustrate a line group with its controlling apparatus and relays for selecting a calling line in such group. Fig. 3 illustrates the associated group of plug ended trunk cords and that portion of the apparatus more directly associated with the cords.

Referring to Fig. 1, I have shown at A the complete circuits of one line terminating at the central office in the line relay 41 and in the cut-off relay 43. A second similar line is indicated by the line relay 42 and cut-off relay 44. The line relays 41 and 42, respectively, control the circuits of local relays 121 and 131, and additional lines are indicated by the local relays 122 and 132. Each line is or may be provided with a plurality of connecting spring jacks connected as indicated at 221 and 231, and with connecting terminals on connector switches as indicated at 222 and 232.

Referring to Fig. 3, I have shown at C the complete circuits and apparatus of one of the group of plug ended trunks associated with the line group of Fig. 1, and have indicated a plurality of such trunks by the conductors terminating in plug D and by the circuit controlled at the left hand contact levers of relays 81 and 91 extending through corresponding contact levers of similar relays 82—92 and 80—90 of other similar trunks. While the symbol indicating the central battery has been repeatedly shown throughout the drawings, it is to be understood that this is for the sake of simplicity, and that the central battery is to be arranged in accordance with the well known practice of the art.

Each trunk line leading to a plug, as at C, is provided with a group of so-called tens relays indicated at 1—2, and with a group of so-called units relays indicated at 11—12 corresponding generally to the similarly characterized relays of the system described in United States Patent No. 1,091,193, issued to E. E. Clement March 24, 1914. Assuming for the purpose of illustration that the line group of Fig. 1 contains one hundred lines, these lines would then be divided into

- sub-groups corresponding to the tens digits of the line numbers. Thus, the first sub-group would contain lines numbering 11, 12, 13, 14, 15, 16, 17, 18, 19 and 10; the second 5 sub-group would contain lines similarly numbered 21 to 20, inclusive, and so on for the entire hundred. Assuming that ten trunks be provided for the one hundred lines, then each trunk would be provided 10 with a tens relay for each sub-group of lines in the contacts of which would terminate the line conductors of the respective sub-group. Thus in Fig. 1 relay 1 is the tens 15 relay of the first sub-group, and relay 2 is the tens relay of the second sub-group. The conductors indicated at E and F are those by which the lines of the first two sub-groups are multiplied to corresponding relays of other trunk lines in the group of ten. 20 Each trunk line is also provided with a group of ten units relays corresponding respectively to the units digits of the line numbers. Thus relay 11 corresponds to all 25 lines having numbers ending in the units digit "1," and relay 12 to all lines having numbers ending in the units digit "2." Each trunk is also provided with a relay 71 for causing the energization of the tens and units relays, and at 72 and 70 I have indicated those relays of the second and last 30 trunks of the group corresponding to relay 71 of trunk C.

Each group of lines and trunks is provided with a group of serially related relays 35 corresponding respectively to the several sub-groups. The relays 101, 102 and 110 correspond respectively to the first, second and last sub-groups of the line group. Additional relays for each sub-group are provided, that for the first sub-group being shown at 141, and for the second sub-group at 142, controlled by the corresponding relays of the serially related group. Another 40 group of ten serially related relays is provided corresponding to the units digits of the several line numbers. Relay 111 corresponds to the units digit one, relay 112 to the units digit two, and the last of the series is relay 120 corresponding to the units 45 digit "0".

The switch indicated at B may be any suitable type of rotary switch, driven one step forward on each retraction of its driving magnet 140. The switch wipers advance 50 always in the same direction without restoring motion and are indicated as provided with ten stationary or bank contacts for each wiper. The left hand group of bank contacts corresponds to the group of relays 55 101, 102 and 110; those of the middle set correspond to the group of relays 111, 112 and 120, while those of the right hand set correspond to the several trunks of the trunk group. The switch B remains normally at 60 rest, but in case of delayed selection its

wipers are advanced changing the order of precedence as between the several trunks of the group, and as between the various lines and sub-groups of lines, as will be subsequently explained. 70

Assuming now that the subscriber at A initiates a call by raising his receiver, a circuit is closed extending from the central battery through the winding of relay 41, the lower contact of relay 43, the sub-station 75 transmitter and receiver, and to earth through the upper contact of relay 43. The ensuing energization of relay 41 disconnects at its right hand contact lever the winding of cut-off relay 43 from the connection terminals at 221 and 222, and connects these terminals to battery through a resistance coil in order that the line may be held busy to outgoing calls during the operation of the selective apparatus. The circuit closed at the left hand contact of relay 41 energizes relay 121. The relays 121, 122, 131 and 132 are to be understood as corresponding respectively to those lines numbered 11, 12, 21 and 22 in the line group of 80 the drawings. The energization of relay 121 closes at its left hand contact through wire 145, a guarding circuit common to all lines of the entire line group, which will be subsequently described. The actuation of the 85 center contact of relay 121 closes a circuit which may be traced from battery through the upper contact of relay 139, wire 151, winding of relay 101, left hand contact of relay 134, and wire 150 to earth through the 90 center contact of relay 121. The ensuing energization of relay 101 closes at its center contact a locking circuit in shunt of the left hand contact of relay 134. The left hand contact of relay 101 completes the 95 circuit of relay 134, which thereupon breaks the normal circuits leading to the windings of each of the serially related group of relays, including relay 101, the latter relay, however, remaining energized because of its 100 locking contact having been previously closed. By the actuation of the right hand contact lever of relay 101, a circuit is completed leading from ground through the left hand wiper of switch B, the right hand 105 forward contact of relay 101, and winding of relay 141 to battery. The operation of relay 141 closes at its right hand contact an earth connection for wire 159 leading to the left hand contact of relay 71. At the same time a circuit is completed leading from ground through the right hand contact of relay 121, the center contact of relay 141, wire 155, the left hand contact of relay 135, the winding of relay 111, wire 151, and to 110 battery through the upper contact of relay 139. The resulting energization of relay 111 completes at its center contact a locking circuit in shunt of the left hand contact of relay 135; completes at its left hand contact 115

an energizing circuit for relay 135, which thereupon breaks the normal circuits leading to the windings of the group of relays in which relay 111 is located; and at the 5 right hand contact lever of relay 111 completes a circuit which may be traced from ground through the center wiper of switch B, the forward right hand contact of relay 111, and to the center contact of relay 71. 10 By the operations so far described, it will be seen that the energization of local relay 121 of line 11 has resulted in the placing of an earth connection on the left hand contact of relay 71 corresponding to the first tens 15 relay shown at 1, and in the placing of a ground on the middle contact of relay 71 corresponding to the first units relay shown at 11. At the same time the actuation of 20 relays 134 and 135 has prevented the operation of the associated serially related groups of controlling relays in which are located relays 101 and 111. If line No. 12 had been the calling line, then the operation of relay 122 would have grounded those contacts of 25 relay 71 corresponding to the first tens relay 1, and to the second units relay 12. Similarly, line 21 in calling would energize 30 relay 131 grounding those contacts of relay 71 corresponding to the second tens relay 2 and to the first units relay 11.

Assuming that the first idle trunk of the trunk group is that indicated at C and that the wipers of switch B are resting in the position indicated, the energization of relay 35 111 has closed a circuit which may be traced from battery through the winding of relay 71, wire 76, the contact of relay 235 to which this wire leads, wire 75, left hand contact of relay 81, wire 158, right hand wiper of 40 switch B, wire 152, and to earth at the now closed left hand contact of relay 111. The resulting energization of relay 71 completes at its left hand contact the energizing circuit for relay 1, and at its middle contact 45 the energizing circuit for relay 11. The ensuing energization of relays 1 and 11 extends the talking conductors 86 and 87 of line A to connection with the talking conductors 84 and 89 of trunk C. At the same time a circuit 50 is completed at the contacts of these relays leading from battery through the winding of relay 81, and to earth at the second contact down of relay 1. The operation of the right hand contact of relay 81 completes 55 through wire 77, left hand contact of relay 177, wire 78 and resistances 13 and 14, locking circuits for relays 11 and 1, respectively, these circuits being completed at contacts 79 and 81 of the respective relays. By the operation 60 of relay 71 a circuit has also been closed at its right hand contact leading to battery through the winding of sluggish relay 91. The time characteristic of this relay is such that following the interruption of 65 its circuit at relay 71, it will remain ener-

gized for a sufficient length of time to prevent the closing of its left hand contact until after ground has been removed from wire 152 by the retraction of the previously energized relay 111 or other corresponding relay 70 in the same group. The operation of the left hand contact lever of relay 81 interrupts the energizing circuit of relay 71, and at its forward contact extends the circuit of wire 158 to the contact lever of relay 91. 75 Upon the subsequent deenergization of relay 91, the circuit of wire 158 is thereby extended to a relay 72 or 70 of the next idle trunk corresponding to relay 71 of trunk C.

Returning now to relays 1 and 11, the extension of talking conductors 86 and 87 by the operation of these relays has completed a circuit which may be traced from battery through the winding of impedance coil 179 (Fig. 3) conductor 89, conductor 88, conductor 87, and through the lower winding of cut-off relay 43 to earth. The energization of relay 43 over this circuit interrupts the normal circuits of line A releasing relay 41 and connecting the two talking conductors 90 of the line to conductors 87 and 86. Additional current will now flow through winding of impedance 179 and the line limbs, then dividing and a portion flowing through the upper winding of relay 43 and a portion to 95 earth through conductors 86, 85, 84, and the winding of relay 178 to ground. The release of line relay 41 releases local relay 121, which in its turn releases relays 101, 141, 134, 111 and 135, thereby restoring to normal 100 the controlling circuits of Fig. 2 leaving them in readiness for a second calling line. The retraction of the right hand contact lever of relay 41 again connects the contact terminals at 221 and 222 to the lower winding of relay 43, and these terminals are now held busy by reason of the battery potential supplied through the impedance 179. In case of another call, as for example line 21, then the resulting energization of relay 131 110 would cause the operation of relay 72 or the corresponding relay of the next idle trunk in the serially related group.

Before taking up the operation of the apparatus illustrated in Fig. 3, it should be 115 pointed out that as here illustrated, the trunk lines of each group terminate in plugs located each at a different answering operator's position. Under this arrangement therefore, each plug located before an answering operator represents a different group of trunk lines, and therefore a different group of subscribers' lines. Starting, therefore, with the assumption of one hundred subscribers' lines to a group and of ten 120 trunks in the group associated therewith, these trunks would then terminate at ten different operators' positions. Assuming that each operator could handle ten such trunks, there would then be ten groups of 125 130

lines or one thousand lines divided into groups of one hundred and each one hundred line group having access to a group extending to each one of the ten operators of the system. With this understanding, it is to be explained that relay 235 shown on Fig. 3 is a relay common to that operator before whom is located the plug shown at C. The circuit represented by wires 76, 75 and 82 10 extending to the contact pieces of relay 235 relates to the group of trunks associated with line A. The circuit represented by the wires leading to the left hand group of contacts of relay 235 relates to an entirely different group of lines and trunks in the system, and relay 235 is to be understood to be equipped with as many sets of contacts as there are trunks like that shown at C terminating at the operator's position to which 15 relay 235 belongs. Each such set of contacts therefore controls the circuit of a different group of trunks; and the circuit closed through the right hand wiper of switch B of any line group may therefore extend 20 through the contacts of each relay 235 of the ten operators' positions.

Referring back now to the operation of relay 81 following the initiation of a call at A, the operation of the right hand contact 30 of this relay has closed a circuit which may be traced from battery through lamp 182, the center normally closed contact of relay 175, wire 77, and to earth at the right hand contact of relay 81, illuminating lamp 182 35 to constitute a call signal for the operator. At the same time a circuit is closed leading from battery through the winding of relay 235, the upper contact of relay 176, and to earth through the circuit previously traced 40 for lamp 182. The operation of relay 235 by the operation of that contact lever to which wire 75 leads, disconnects the circuit of relay 71 of trunk C and extends wire 75 through the forward engaging contact of 45 wire 82, and thence through the contact of relay 91 to relay 72 of the next trunk in the group containing C. By a similar operation of the other contact levers of relay 235, the relays corresponding to 71 of all other 50 trunks terminating at the position of relay 235 are disconnected, and the normal circuits leading to these relays are extended to the corresponding relays of the trunks next in serial relation in their respective groups. 55 The relay 235 remains energized as long as the lamp 182 or the corresponding lamp of any other trunk remains illuminated at the operator's position with which relay 235 is associated; thereby preventing a second call 60 from being extended to a trunk on such position during such illumination.

Upon observing lamp 182, the operator actuates her listening key H thus connecting her telephone circuit 191—192 with the talk 65 ing conductors of the trunk and her busy

test circuit 193 with the tip of the plug at C. Upon receiving the call number of the desired line, the operator completes the connection either by plugging directly into a multiple jack of the desired line, or by plugging into the jack of a trunk by means of which the desired connection may be completed. Assuming that the plug be inserted into a jack connected like that shown at 231, Fig. 1, a circuit is first completed leading 70 from battery through the winding of relay 172, the sleeve strand of the plug, the thimble of jack 231, and to earth through the winding of cut-off relay 44. The energization of relay 172 at its right hand contact 75 disconnects the busy test circuit leading to 193 completing the tip, strand of the plug circuit; and at its left hand contact completes the circuit of supervisory lamp 181 and of relay 180. The closing of right hand 80 contact of relay 180 energizes relay 175, and the closing of the left hand contact of relay 180 completes a circuit for maintaining relay 174 energized through the ground at left hand contact of relay 172. Relay 174 was 85 initially energized by the circuit including wire 77 closed at relay 81. Bearing in mind that relay 178 is now energized by current flowing through the sub-station at A, the operation of the upper contact lever of relay 90 95 175 is at this time ineffective. The operation of the middle contact lever of relay 175 interrupts the previously established circuit for lamp 182 extinguishing the lamp; and by the engagement of the associated forward contact closes an energizing circuit for relay 176. Relay 176 in operating completes at its lower contact a locking circuit leading to the right hand contact of relay 81; and at its upper contact interrupts the circuit of 100 relay 235, thereby rendering the other trunk circuits of the operator's position available for selection. By the operation of relays 174 and 175 a circuit has been completed effective to apply ringing current to the line as 105 110 sociated with cut-off relay 44 in a manner now to be explained. For applying ringing current to the plug indicated at C, I provide sets of cam actuated contacts a^1 , a^2 , a^3 and a^4 . The cams for actuating these contacts 115 are rigidly secured to a common rotating shaft which is driven by a stepping magnet 171. A ratchet wheel secured to the common shaft is engaged by a driving pawl carried by the armature of magnet 171 and advanced one step at each retraction of the magnet armature. The ratchet wheel and shaft may be regarded as moving always in a clockwise direction and may be provided with twelve teeth. 120 125

Upon the energization of relay 175 previously described, a circuit may then be traced leading from battery through the winding of relay 237, contact of relay 236, winding of magnet 171, right hand forward 130

contact of relay 174, lower forward contact of relay 175, and thence to earth through conductor 77 and the right hand contact of relay 81. Current flowing in this circuit energizes relay 237, which completes at its left hand contact a direct battery connection for magnet 171, energizing said magnet, and at its right hand contact an energizing circuit for relay 236. The energization of relay 236 interrupts the circuit of relay 237, which thereafter releases its armature causing the cams at a^1 , a^2 , a^3 and a^4 to be advanced one step. Relays 236 and 237 are sluggish relays, their time characteristic being such that they will continue to vibrate stepping the cams at a suitable rate as long as circuit remains closed through magnet 171. At the first step of the cams following the insertion of the plug C, the contact lever of each set a^1 , a^2 , a^3 and a^4 is actuated. The lever at a^1 interrupts the normal circuit of the tip cord strand and connects the plug tip with the lever of contacts a^2 . The operation of this latter contact lever connects the lever with a source of alternating ringing current. The operation of contact lever at a^3 connects the resistance 185 to the sleeve strand of the cord in shunt of the winding of relay 172, thereby providing a return path for the ringing current. The actuation of the contact lever at a^4 is without effect at this time. During the second, third and fourth steps of the cams, ringing current flows over the line of the called subscriber causing the operation of the sub-station bell. At the fifth step of the cams contact lever at a^2 is restored disconnecting the ringing current source and establishing a direct connection between the tip and sleeve of the plug to discharge the line. At the sixth step, the levers at a^1 and a^3 restore, thus reestablishing the talking circuit of the cord strands. Following the sixth step of the cams and assuming that the called subscriber responds, current flowing through the sub-station telephone is effective to energize relay 173, in which case the interruption at the contact of this relay extinguishes lamp 181 and releases relay 174. The release of relay 174 closes at its right hand contact lever an alternative circuit for magnet 171 through the contact of cam springs a^4 , thereby causing the continued stepping of the cams and associated shaft until contact lever a^4 is restored at the twelfth step of the cams. In case the called subscriber does not answer during the first twelve steps of the cam mechanism, its cycle of operation is repeated indefinitely until such response has occurred or until the calling subscriber replaces his telephone.

Following the restoration of the receiver of the calling subscriber either in case of no answer from the called subscriber or at the conclusion of conversation, the resulting

release of relay 178 causes the illumination of lamp 182, and with the illumination of lamp 181 giving the disconnect signal to the operator. The plug at C is thereupon removed from the spring jack thereby releasing relay 172. The release of relay 172 interrupts at its left hand contact the circuit of relay 180, which in turn interrupts at its right hand contact the circuit of relay 175. Relay 175 in dropping back establishes a circuit which may be traced from battery through the winding of relay 177, the middle contact of relay 176, the upper contact of relay 175, and the contact of relay 178. Current in this circuit energizes relay 177 which actuates its contact interrupting the circuit of wire 78 and thereby releasing relays 1 and 11, disconnecting the calling line from a trunk line. The interruption at the contacts of relays 1 and 11 releases relay 81 which, by the interruption of its right hand contact, releases relay 176. The restoration of the left hand contact lever of relay 81 reestablishes the connection of relay 71, thereby leaving the trunk C now in condition for use with a subsequently calling line.

Referring now to the switch B, the wire 152 leading to the right hand wiper of this switch may be characterized as a "start" wire, and when ground is applied to this wire by the operation of any one of the series of relays, including relay 111, a circuit is closed leading to relay 71 of that idle trunk of the associated group most directly connected with the right hand switch wiper. The wires leading from the contacts engaged by this wiper are carried directly to the left hand contact levers of those relays of the group of trunks corresponding respectively to relay 81. By reason of these wires, if the switch B be advanced the order of precedence as between the several trunks of the group is changed at each step of the switch, that trunk corresponding to the contact upon which the wiper is resting being always the first trunk in the order of precedence. Similarly, the wires leading from the middle group of stationary contacts of the switch B serve to determine the order of precedence as between the relays of the group containing relay 111. In case a plurality of these relays be simultaneously energized, then only that relay whose right hand contact lever is most directly connected to the switch wiper becomes effective to apply ground to wire 161; and shifting the middle wiper changes the order of precedence as between these relays. A similar relation exists with respect to the relay group containing relay 101 and the left hand wiper and contacts of switch B.

In case of abnormal delay or failure to connect a calling line with an idle trunk, then the common guarding circuit includ-

ing wire 145 becomes effective to cause the advance of switch B and successively change the order of precedence as between the several trunks of a group and as between the several line groups represented by the left hand wiper, and as between the several lines of a group as represented by the middle wiper. Relay 137 is a relay made sufficiently slow to release that its energization will be maintained during any normal period of interruption of its circuit by the energization of relay 136 in response to an operation of any relay of the group corresponding to relay 121. Relay 136 is held energized as long as a relay 121 of any line in the group remains energized, and therefore, if due to delay or failure to select a calling line, relay 121 is not released within a normal period of time, relay 137 becomes deenergized. Upon its release an alarm circuit is closed at N. A. by the operation of its left hand contact; and the closing of its right hand contact establishes an energizing circuit for switch magnet 140 including the contact of relay 138. The magnet 140 on actuation closes at its upper contact a circuit of relay 139. The operation of the lower contact of relay 139 closes the circuit of relay 138, which in turn interrupts the circuit of driving magnet 140 causing the wipers of switch B to be advanced one step on the retraction of the driving magnet armature. At the same time, the interruption of circuit through wire 151 at the upper contact of relay 139 releases any previously energized relays in or controlled by the groups containing relays 101 and 111. The release of the driving magnet armature breaks the circuit of relay 139, which upon restoring reestablishes the circuit of wire 151 allowing the reenergization of those relays controlled in groups 101 and 111, or of other relays controlled in these groups due to the presence of other calling lines which may have been placed earlier in order of preference by the advance of the switch or the release of the previously energized relays. This operation is repeated until by the advance of the switch B that portion of the line or trunk apparatus responsible for the delay or failure has been withdrawn from service and all lines then calling properly selected.

It will be apparent from the above description that each group of trunks for a group of lines is provided with an individual start wire for the group, and that each start wire is extended through a relay 235 at each operator's position. Upon the illumination of a call lamp 182 at any position, the operation of the associated relay 235 disconnects the several start wires from the several trunks of such position extending the start wires directly to the trunks of the position next in serial relation. By this

means the calls are distributed to the several operators only so fast as they are answered, and calling lines are thus always extended to idle operators' positions.

While I have assumed for purpose of illustration a certain number of operators' positions and a certain number of trunks per operator, it is to be understood that this distribution of trunks and operators may be modified to any desired extent. Similarly, the size of the line groups and trunk groups here assumed has been for purpose of illustration only and may be modified as desired. My invention is not limited to the precise arrangement here disclosed, as it may be embodied in many different forms.

I claim:

1. A telephone exchange system comprising a plurality of calling lines divided into sub-groups, a trunk line for said plurality terminating in a connecting plug at an operator's position, a group of relays for said trunk line said relays corresponding individually to the sub-groups of lines, a group of relays for said trunk line said relays corresponding individually to corresponding lines in each sub-group, means for energizing a relay of each of said groups to connect any calling line with said trunk line, a spring jack for said connecting plug, and means to maintain a locking circuit for an energized pair of said relays while said plug is resting in said spring jack. 75

2. A telephone exchange system comprising a plurality of calling lines divided into sub-groups, a trunk line for said plurality terminating in a connecting plug at an operator's position, a group of relays for said trunk line said relays corresponding individually to the sub-groups of lines, a group of relays for said trunk line said relays corresponding individually to corresponding lines in each sub-group, means for energizing a relay of each of said groups to connect any calling line with said trunk line, a spring jack for said connecting plug, and releasing means for an energized pair of said relays placed under control of an associated calling line following the connection and subsequent disconnection of said plug with said spring jack. 100

3. A telephone exchange system comprising a plurality of calling lines divided into sub-groups, a trunk line for said plurality terminating in a connecting plug at an operator's position, a group of relays for said trunk line said relays corresponding individually to the sub-groups of lines, a group of relays for said trunk line said relays corresponding individually to corresponding lines in each sub-group, means for energizing a relay of each of said groups to connect any calling line with said trunk line, a spring jack for said connecting plug, and a supervisory signal associated with 105 120 125 130

said plug responsive to control by an associated calling line while said plug is resting in said spring jack.

4. A telephone exchange system comprising a plurality of calling lines divided into sub-groups, a trunk line for said plurality terminating in a connecting plug, a group of relays for said trunk line said relays individually corresponding to the sub-groups of lines, a group of relays for said trunk line said relays individually corresponding to corresponding lines in each sub-group, switching means for momentarily energizing a relay in each group to connect any calling line with said trunk line, and a locking circuit for said relays established responsive to their momentary energization.
5. A telephone exchange system comprising a plurality of calling lines divided into sub-groups, a trunk line for said plurality terminating in a connecting plug at an operator's position, a group of relays for said trunk line said relays corresponding individually to the sub-groups of lines, a group of relays for said trunk line said relays corresponding individually to corresponding lines in each sub-group, means for energizing a relay of each of said groups to connect any calling line with said trunk line, means for associating said connecting plug with the line of a called subscriber, a supervisory signal associated with said plug responsive to control by an associated calling line, and a supervisory signal associated with said plug responsive to control by an associated called line.

6. A telephone exchange system comprising a plurality of calling lines divided into sub-groups, a trunk line for said plurality terminating in a connecting plug at an operator's position, a group of relays for said trunk line said relays corresponding individually to the sub-groups of lines, a group of relays for said trunk line said relays corresponding individually to corresponding lines in each sub-group, means for energizing a relay of each of said groups to connect any calling line with said trunk line, means for associating said connecting plug with the line of a called subscriber, a supervisory relay for said plug under control of an associated calling line, a supervisory relay for said plug under control of an associated called line, a relay in a local circuit controlled in the manipulation of said plug, and means controlled by said supervisory and local circuit relays for controlling the relays of said groups.

7. A telephone exchange system comprising a plurality of calling lines divided into sub-groups, a trunk line for said plurality, a group of relays for said trunk line said relays individually corresponding to the sub-groups of lines, a group of relays for

said trunk line said relays corresponding individually to corresponding lines in each sub-group, a cut-off relay for each calling line, a line relay for each calling line, a local relay for each of said line relays, and means controlled by said local relay for energizing a relay of each of said groups to connect the associated calling line with said trunk line.

8. A telephone exchange system comprising a plurality of calling lines divided into sub-groups, a trunk line for said plurality terminating in a connecting plug at an operator's position, a group of relays for said trunk line said relays corresponding individually to the sub-groups of lines, a group of relays for said trunk line said relays corresponding individually to corresponding lines in each sub-group, means for energizing a relay of each of said groups to connect any calling line with said trunk line, a called line, a spring jack associated therewith, and means controlled by said plug and spring-jack for automatically connecting said called line in circuit with a source of calling current.

9. A telephone exchange system comprising a plurality of calling lines divided into sub-groups, a trunk line for said plurality terminating in a connecting plug at an operator's position, a group of relays for said trunk line said relays corresponding individually to the sub-groups of lines, a group of relays for said trunk line said relays corresponding individually to corresponding lines in each sub-group, means for energizing a relay of each of said groups to connect any calling line with said trunk line, a called line, a spring jack associated therewith, means controlled by said plug and spring-jack for connecting said called line in circuit with a source of calling current, and means controlled by said called line for discontinuing the connection of said source in circuit therewith.

10. A telephone exchange system comprising calling lines, an operator position, trunks for said lines each terminating in a connecting plug at said position, a signal receiving device associated with each plug, selecting apparatus adapted to connect any calling line with an idle one of said trunks, selection initiating means for said trunks, and means common to said signal receiving devices for controlling said initiating means.

11. A telephone exchange system comprising plural groups of calling lines, an operator position, a trunk for each of said groups each terminating in a connecting plug at said position, a signal receiving device associated with each plug, selecting apparatus adapted to connect any calling lines with an idle one of said trunks, a selection initiating circuit for each of said groups extending

to said position, and means common to said signal receiving device for controlling said initiating circuits.

12. A telephone exchange system comprising a plurality of calling lines divided into sub-groups, a trunk line for said plurality terminating in a connecting plug at an operator's position, a group of relays for said trunk line said relays corresponding individually to the sub-groups of lines, a group of relays for said trunk line said relays corresponding individually to corresponding lines in each sub-group, means for energizing a relay of each of said groups to connect any calling line with said trunk line, a called line, means associated with said plug for connecting said called line in circuit with a source of calling current, and means controlled by said called line for discontinuing the connection of said source in circuit therewith.

13. A telephone exchange system comprising a plurality of calling lines divided into sub-groups, a trunk line for said plurality terminating in a connecting plug at an operator's position, a group of relays for said trunk line said relays corresponding individually to the sub-groups of lines, a group of relays for said trunk line said relays corresponding individually to corresponding lines in each sub-group, means for energizing a relay of each of said groups to connect any calling line with said trunk line, a called line, and means manually controlled at said position for automatically connecting said plug and line in circuit with a source of calling current.

14. A telephone exchange system comprising a plurality of calling lines divided into sub-groups, a trunk line for said lines terminating in a connecting plug at an operator position, a group of relays for said trunk line said relays corresponding individually to the sub-groups of lines, a group of relays for said trunk line said relays corresponding individually to corresponding lines in each sub-group, means for energizing a pair of relays one from each of said groups to connect any calling line with said trunk line, a locking circuit for said pair of relays, and operator controlled means to break said locking circuit following use of said trunk line.

15. A telephone exchange system comprising a plurality of calling lines divided into sub-groups, a trunk line for said lines terminating in a connecting plug at an operator position, a group of relays for said trunk line said relays corresponding individually to the sub-groups of lines, a group of relays for said trunk line said relays corresponding individually to corresponding lines in each sub-group, means for energizing a pair of relays one from each of said groups to

connect any calling line with said trunk line, and means to prevent energizing any relay of said groups other than said pair.

16. A telephone exchange system comprising a plurality of calling lines divided into sub-groups, a cut-off relay for each line, a trunk line for said lines terminating in a connecting plug at an operator position, a group of relays for said trunk line said relays corresponding individually to the sub-groups of lines, a group of relays for said trunk line said relays corresponding individually to corresponding lines in each sub-group, means for energizing a pair of relays one from each of said groups to connect the talking conductors of any calling line with said trunk line, and a separate local conductor including contacts of said pair of relays for controlling said cut-off relay.

17. A telephone exchange system comprising a plurality of calling lines divided into sub-groups, a trunk line for said lines terminating in a connecting plug at an operator position, a group of relays for said trunk line said relays corresponding individually to the sub-groups of lines, a group of relays for said trunk line said relays corresponding individually to corresponding lines in each sub-group, means for energizing a pair of relays one from each of said groups to connect the talking conductors of any calling line with said trunk line, and a separate local conductor including contacts of said pair of relays for controlling said pair of relays.

18. A telephone exchange system comprising a plurality of calling lines divided into sub-groups, a trunk line for said lines terminating in a connecting plug at an operator position, a group of relays for said trunk line said relays corresponding individually to the sub-groups of lines, a group of relays for said trunk line said relays corresponding individually to corresponding lines in each sub-group, means for energizing a pair of relays one from each of said groups to connect the talking conductors of any calling line with said trunk line, a locking circuit for said pair of relays, and a separate local conductor including contacts of said pair of relays for controlling said locking circuit.

19. A telephone exchange system comprising a plurality of calling lines divided into sub-groups, a trunk line for said lines terminating in a connecting plug at an operator position, a group of relays for said trunk line said relays corresponding individually to the sub-groups of lines, a group of relays for said trunk line said relays corresponding individually to corresponding lines in each sub-group, means for energizing a pair of relays one from each of said groups to connect the talking conductors of

any calling line with said trunk line, a locking circuit for said pair of relays, a separate local conductor including contacts of said pair of relays, and means controlled by 5 said local conductor for establishing said locking circuit.

20. A telephone exchange system comprising a plurality of calling lines divided into sub-groups, a trunk line for said lines terminating in a connecting plug at an operator position, a group of relays for said trunk line said relays corresponding individually to the sub-groups of lines, a group of relays for said trunk line said relays corresponding 10 individually to corresponding lines in each sub-group, means for energizing a pair of relays one from each of said groups to connect any calling line with said trunk line, a locking circuit for said pair of relays, 15 and means including serially related contacts of said pair of relays for establishing said locking circuit.

21. A telephone exchange system comprising a plurality of calling lines divided into 25 sub-groups, a trunk line for said lines terminating in a connecting plug at an operator position, an indicator for said trunk line, a group of relays for said trunk line said relays corresponding individually to the sub-groups of lines, a group of relays for said trunk line said relays corresponding 30 individually to corresponding lines in each sub-group, means for energizing a pair of relays one from each of said groups to connect the talking conductors of any calling line with said trunk line, and a separate local conductor including contacts of said pair of relays for controlling said indicator.

22. A telephone exchange system comprising 40 a plurality of calling lines divided into sub-groups, a trunk line for said lines terminating in a connecting plug at an operator position, a group of relays for said trunk line said relays corresponding individually to the sub-groups of lines, a group of relays for said trunk line said relays corresponding 45 individually to corresponding lines in each sub-group, means for energizing a pair of relays one from each of said groups to connect the talking conductors of any calling line with said trunk line, and a separate local conductor including contacts of said pair of relays for controlling said energizing means.

23. A telephone exchange system comprising 55 a plurality of calling lines divided into sub-groups, a trunk line for said lines terminating in a connecting plug at an operator position, a group of relays for said trunk line said relays corresponding individually to the sub-groups of lines, a group of relays for said trunk line said relays corresponding 60 individually to corresponding lines in each sub-group, means for energizing a pair of relays one from each of said groups to

select and connect the talking conductors of any calling line, selection initiating means for said lines, and a separate local conductor including contacts of said pair of relays for controlling said initiating means.

70

24. A telephone exchange system comprising a plurality of calling lines divided into sub-groups, a trunk line for said lines terminating in a connecting plug at an operator position, a group of relays for said 75 trunk line said relays corresponding individually to the sub-groups of lines, a group of relays for said trunk line said relays corresponding individually to corresponding lines in each sub-group, means for energizing a pair of relays one from each of said groups to select and connect the talking conductors of any calling line, selection initiating means for said lines associated with said trunk line, and a separate local conductor including contacts of said pair of relays for disassociating said initiating means 80 from said trunk line.

80

25. A telephone exchange system comprising a plurality of calling lines divided into 90 sub-groups, a trunk line for said lines terminating in a connecting plug at an operator position, a group of relays for said trunk line said relays corresponding individually to the sub-groups of lines, a group 95 of relays for said trunk line said relays corresponding individually to corresponding lines in each sub-group, means for energizing a pair of relays one from each of said groups to connect the talking conductors of 100 any calling line with said trunk line, a separate local conductor including contacts of said pair of relays, another trunk line, and means controlled by said local conductor for associating said other trunk line with said 105 lines.

100

26. A telephone exchange system comprising a plurality of calling lines divided into sub-groups, a trunk line for said lines terminating in a connecting plug at an operator position, a group of relays for said trunk line said relays corresponding individually to the sub-groups of lines, a group 110 of relays for said trunk line said relays corresponding individually to corresponding lines in each sub-group, means for energizing a pair of relays one from each of said groups to connect the talking conductors of any calling line with said trunk line, a separate local conductor including contacts of 115 said pair of relays, and ringing means for said plug controlled by said local conductor.

115

27. A telephone exchange system comprising a plurality of calling lines divided into sub-groups, a trunk line for said lines terminating in a connecting plug at an operator position, a group of relays for said 120 trunk line said relays corresponding individually to the sub-groups of lines, a group of relays for said trunk line said relays corresponding 125 individually to corresponding lines in each sub-group, means for energizing a pair of relays one from each of said groups to

130

responding individually to corresponding lines in each sub-groups means for energizing a pair of relays one from each of said groups to connect the talking conductors of any calling line with said trunk line, and a separate local conductor for said trunk line including serially related contacts of said pair of relays.

28. A telephone exchange system comprising a plurality of calling lines divided into sub-groups, a trunk line for said lines terminating in a connecting plug at an operator position, a group of relays for said trunk line said relays corresponding individually to the sub-groups of lines, a group of relays for said trunk line said relays corresponding individually to corresponding lines in each sub-group, means for energizing a pair of relays one from each of said groups to connect the talking conductors of any calling line with said trunk line, a locking circuit for said pair of relays, and a local circuit for said trunk line separate from said talking conductors controlled by said locking circuit.

29. A telephone exchange system comprising a plurality of calling lines divided into sub-groups, a trunk line for said lines terminating in a connecting plug at an operator position, a group of relays for said trunk line said relays corresponding individually to the sub-groups of lines, a group of relays for said trunk line said relays corresponding individually to corresponding lines in each sub-group, means for energizing a pair of relays one from each of said groups to connect the talking conductors of any calling line with said trunk line, a locking circuit for said pair of relays, and a local circuit including contacts of said pair of relays separate from said conductors controlled by said locking circuit.

30. A telephone exchange system comprising a plurality of calling lines, a trunk line for said lines terminating in a connecting plug at an operator position, a group of relays, means for energizing certain of said relays to connect any calling line with said trunk line, operator controlled means for said trunk line, and a locking circuit for said certain relays maintained until after actuation of said operator controlled means.

31. A telephone exchange system comprising a plurality of calling lines, a trunk line for said lines terminating in a connecting plug at an operator position, a group of relays, means for energizing certain of said relays to connect any calling line with said trunk line, operator controlled means for said trunk line, and a signal to indicate connection of a calling line maintained active until after actuation of said operator controlled means.

32. A telephone exchange system comprising a plurality of calling lines, a trunk line

for said lines terminating in a connecting plug at an operator position, a group of relays, means for energizing certain of said relays to connect any calling line with said trunk line, a spring jack for connecting to a wanted line, and means to prevent de-energization of said certain relays during the presence of said plug in said spring jack.

33. A telephone exchange system comprising a plurality of calling lines, a trunk line for said lines terminating in a connecting plug at an operator position, a group of relays, local relays for momentarily energizing certain relays of said group to connect any calling line with said trunk line, and means controlled by said plug to maintain energization of said certain relays.

34. A telephone exchange system comprising a plurality of calling lines, a trunk line for said lines terminating in a connecting plug at an operator position, a group of relays, and local relays for momentarily energizing certain relays of said group to connect any calling line with said trunk line.

35. A telephone call distributing system comprising a plurality of calling lines, a plurality of operators' positions, a plurality of trunks terminating at each operator's position, means for selecting idle trunks and connecting calling lines therewith, a plurality of circuits extending to the trunks at each position over which such selecting means may be started in operation, operator controlled means associated with each trunk, a device common to the position controlled from said operator controlled means for temporarily disabling the starting circuits extending to such position.

36. A telephone call distributing system comprising a plurality of calling lines, a plurality of operators' positions, a plurality of trunks terminating at each operator's position, means for selecting idle trunks and connecting calling lines therewith, a plurality of circuits extending to the trunks at each position over which such selecting means may be started in operation, operator controlled means associated with each trunk, a relay common to the position controlled from said operator controlled means for temporarily disabling the starting circuits extending to such position.

37. A telephone call distributing system comprising a plurality of lines arranged in groups, a plurality of operators' positions, a plurality of trunks terminating at each position, selecting means for associating calling lines of each group with trunks at each position, circuits for starting such selecting means in operation extending from a plurality of groups of lines to each position, operator controlled means at each operator's position, and a device common to the position, for disabling all of the start-

ing circuits extending to such position, rendered operable by such operator controlled means.

38. A telephone call distributing system comprising a plurality of lines arranged in groups, a plurality of operators' positions, a plurality of trunks terminating at each position, selecting means for associating calling lines of each group with trunks at each position, circuits for starting such selecting means in operation extending from a plurality of groups of lines to each position, a call signal individual to each trunk

adapted to be displayed when a calling line is connected to such trunk, and a device rendered operable during the display of such signal for temporarily disabling all of the starting circuits extending to the position at which such trunk terminates. 15

In witness whereof, I affix my signature 20 in the presence of two witnesses.

HARRY G. WEBSTER.
